CLOTHESLINE PROP

Ira D. Hartman and Clarence P. Hartman, Stony Creek Mills, Pa.

Application March 9, 1937, Serial No. 129,934

1 Claim. (Cl. 248—353)

This invention relates to props of the type used for supporting sagging clothes-lines, and the object of the invention is to provide a prop of this character that is longitudinally adjustable; and also to provide improved means for securing the sections of the prop at the desired relative position of adjustment.

The invention, together with its objects and advantages, will be best understood from a study 10 of the following description taken in connection with the accompanying drawings, wherein:

Figure 1 is an elevational view of the prop.

Figure 2 is an edge view of the prop.

Figure 3 is a fragmentary detail view partly in 15 section and partly in elevation illustrating certain details hereinafter more fully referred to.

Figure 4 is a fragmentary elevational view of one section of the prop illustrating certain details also hereinafter more fully referred to.

Figure 5 is a perspective view of an end portion 20 of one section of the prop with parts removed therefrom, and

Figure 6 is a perspective view of a latch member.

Referring to the drawings by reference numerals, it will be seen that the improved clothes-line prop comprises two sections 5, 6. Each section is formed of wood, metal, or other suitable material, and is of any desired length, width, and thickness.

30 The section 5 is provided in one end thereof with a suitable notch 7 to accommodate the clothes-line, while the section 6 has one end thereof sharpened to a point as at 8 to penetrate the ground.

35 The prop sections 5 and 6 are arranged in overlapping sliding relation and carried on the free end of the prop section 5 is a sleeve 9 of metal or other suitable material which embraces the prop section 6.

40 Secured to the free end of the prop section 6 is a second sleeve 10 of metal or other suitable material and which embraces the section 5. Thus, it will be seen that sleeves 9 and 10 serve to hold the sections 5 and 6 in assembled overlapping sliding relation for longitudinal adjustment relative to one another.

45 The sleeve 10, which is formed from an oblong sheet of metal or other suitable material, folded into a substantially rectangular frame or sleeve-like form, has its ends secured in overlapping relation to one another through the medium of screws or other fastening elements 11, which latter also serve to secure the sleeve 10 to the prop section 6. One of the ends of the sheet 50 from which the sleeve 10 is formed is provided

5 with a slot 12 that cooperates with the lapped end of said sheet of material to provide in one side of the sleeve 10 an opening that accommodates the shank portion 13 of a latch member indicated generally by the reference numeral 14.

The prop section 6 is provided with a recess 15 in one face thereof that registers with the opening 12 and at opposite sides of the recess is provided with semi-cylindrical recesses 16 that accommodate the opposite ends of a pivot pin 17.

10 Disposed on the pivot pin 17 is a sleeve 18 that is provided on one end of the shank 13 of the latch member 14. The sleeve 18 is accommodated within the recess 15, while the sleeve 10 serves to retain the ends of the pivot pin 17 within the 15 recesses 16.

15 Formed integral with the shank 13 at the free end of the latter and extending at an angle to the shank 13 is a frame-like member 18' through which the prop sections 5 and 6 work, and the member 18' is adapted to engage a selected one of a vertical series of notches 19 provided in one side of the prop section and in a manner clearly shown in Figure 3 to secure the prop sections 5 and 6 at the desired longitudinal position of adjustment.

20 Suitably secured to the shank 13 at the end thereof provided with the frame-like part 18' is a button 20 in the form of a disk hollowed out to provide a socket accommodating one end of a 30 coil spring 21, the opposite end of which coil spring is accommodated within a recess 22 provided in the prop section 6. Spring 21, as will be clear from a study of Figure 3, serves to urge the shank 13 outwardly away from the prop 35 section 6 and an end of the part 18' of the latch member 14 into engagement with a notch 19 to secure the prop sections 5 and 6 against longitudinal relative movement after the sections have been disposed at the desired position of adjustment.

40 The button 20 also serves as a bearing surface for the thumb to facilitate the pressing inwardly of the shank 13 against the action of spring 21 to move the member 18' out of engagement with the notch 19 whereby the prop sections 5 and 6 are free to be spread longitudinally relative to one another, to a desired position of adjustment, upon release of pressure thereon, spring 21 acting to engage the member 18' with the proper notch 45 19 to secure the prop sections at the desired position of adjustment.

45 Preferably, and as shown in Figure 6, the latch member 14 is formed from a single length of wire 50 rod bent into shape to provide the shank 13, the 55

frame section 18', and coiled at the end of the shank 13 to provide the sleeve 18 that accommodates the bearing pin 17.

- It is thought that the manner of using the prop is well known to those skilled in the art, the prop after being secured at the desired adjustment being used for supporting the sagging portion of a line, the line being accommodated in the notch 7 and a pointed end 8 of the prop 10 penetrating the ground; the prop, when properly adjusted, serving to support the sagging part of the line at an elevation suitable to prevent the garments or the like hanging on the line from sweeping the ground.
- 15 The utility and advantages of a prop embodying the features of construction comprehended by the present invention will be clear to those skilled in the art, and having thus described the invention, what is claimed as new is:
- 20 A prop of the class described comprising a pair of upper and lower bars having rear slidably engaging faces, a guide sleeve for said bars se-

cured to the upper end of the lower bar and surrounding both bars, said sleeve having a central aperture in the front face and the lower bar having a recess in the front face thereof registering with said aperture and a pair of laterally extending grooves therein upon opposite sides of the recess and closed by said sleeve, a pivot pin disposed in said grooves to traverse said recess and held in said grooves by said sleeve, a latch arm extending from said pin through said aperture and having a sleeve-like end mounted on said pin rotatably and housed in said recess, said arm having a lower bail-like end surrounding both bars and movable by said arm to engage and disengage the front face of the upper bar, 15 and a spring interposed between said arm and the front face of the lower bar and urging said bail into engaging relation, the front face of the upper bar having notches therein receiving said bail.
